UNITED STATES PATENT OFFICE.

CHARLES KINGSTON WELCH, OF COVENTRY, ENGLAND.

DESIGN FOR A TIRE.

SPECIFICATION forming part of Design No. 31,645, dated October 10, 1899.

Application filed June 6, 1899. Serial No. 719,615. Term of patent 14 years.

To all whom it may concern:

Be it known that I, CHARLES KINGSTON WELCH, engineer, a subject of the Queen of Great Britain, residing at Park House, Coventry, England, have invented and produced a new and original Design for Tires for Bicycles, of which the following is a specification.

This invention relates to a new and original design for tires for bicycles and other vehicles, and more particularly pneumatic tires.

According to my new design the outer or tread surface of a tire is formed with a plain or arched central portion, on each side of which are two contiguous longitudinal undulatory ridges of approximately rectangular shape in cross-section. The ridges of each pair are disposed in such manner that the crests of one ridge break joint with the crests of the other ridge. Arranged centrally upon each ridge is a continuous rib or projection of triangular shape in cross-section.

In the accompanying drawings, Figures 1,

2, and 3 show a portion of the tire-cover with the new design. Fig. 1 is a plan with the cover spread flat. Fig. 2 is a transverse section on the line *x-x* of Fig. 1, and Fig. 3 is an edge elevation of the cover shown flat. Fig. 4 is a side view of a complete tire made in accordance with my design.

The central arched portion of the tire-cover above described is marked A, the rectangular undulatory ridges are marked B, and the continuous triangular ribs are marked C.

What I claim is—

The design for a tire as herein shown and described.

In testimony whereof I have hereunto set my hand, in presence of two subscribing witnesses, this 26th day of May, 1899.

CHARLES KINGSTON WELCH.
